N. H. BRUCE, OF FORGE VILLAGE, WESTFORD, MASSACHUSETTS.

Letters Patent No. 60,856, dated January 1, 1867.

IMPROVEMENT IN TAGS OR LABELS.

The Schedule referred to in these Letters Patent and making part of the same.

TO ALL WHOM IT MAY CONCERN:

Be it known that I, N. H. BRUCE, of Forge Village, Westford, in the county of Middlesex, and State of Massachusetts, have invented a new and improved Tag or Label-Card; and I do hereby declare that the following is a full, clear, and exact description thereof, which will enable others skilled in the art to make and use the same, reference being had to the accompanying drawings, forming part of this specification.

The present invention relates to tags or label-cards, such as are attached to bundles, packages, bags, and other articles, by means of a string or cord or other equivalent line; and it consists in a novel manner of securing the cord or line to the tag, which is accomplished by nipping and fastening the cord in a hollow tube or case, made of metal or other material which will not be torn or cut by the cord if the cord is pulled, which tube or case is secured to the card or tag at one of its ends by folding such end over the same, and glueing or otherwise cementing or securing the whole together, suitable holes being made in the edge of the overlapped portion for the ends of the cord or other string to pass through, for use in tying the label to a bundle, bag, or other parcel or article.

In the accompanying plate of drawings my improvement in tags, label-cards, etc., is illustrated—

Figure 1 being a view of a tag or label-card broken out or away at the proper point to show my manner of fastening a cord to it; and

Figure 2, a section taken in the direction of the length of the tag, and in the plane of the line $z z$, fig. 1.

Similar letters of reference indicate like parts.

A in the drawings represents the tag or label-card, which may be made of paper, card-board, or any other suitable material therefor, and of any desired size and shape. One end, B, of this tag is folded over upon the main portion, C, where, by means of cement, glue, or other suitable adhesive material, it is secured with a metallic tube or case, D, in and between the layers. Through this tube or case, D, previous to its attachment to the label-card as above stated, a cord, string, or other line, F, is passed or drawn, so as to project from each end of the same, which cord is secured therein by nipping the "tube," or in any other proper manner. This cord, when the tube is secured to the label-card, passes through suitable apertures, a, made in the folded edge E of the same, so as to be free for tying the card to a bundle, or package, or bag, or other parcel or article. By securing the cord in a metallic casing or tube, D, which tube is attached to the tag or label-card, the breaking, tearing, or cutting away of the material of which the tag is made, (which is usually paper, card-board, and other similar materials,) by the cord or string is entirely obviated, as the string acts upon the metallic tube in lieu of upon the paper, etc., thus producing a more serviceable, durable, and better tag or label-card than any heretofore used, as is obvious without any further explanation. The tube or casing for the string or cord may be of various shapes and sizes, and therefore I do not intend to limit myself to any one particular size or shape for the same, nor to any one particular material of which it may be made, it being only necessary to use a material for the same that cannot be cut or torn by the string or cord employed.

I claim as new, and desire to secure by Letters Patent—

A tag having a cord or string, or its equivalent, secured to it by passing such cord through a metallic tube or casing, or its equivalent, attached to the tag, substantially as and for the purpose described.

The above specification of my invention signed by me this 31st day of August, 1866.

N. H. BRUCE.
